DESIGN FOR A BEDSTEAD

Norman Bel Geddes and Frances R. Waite, New York, N. Y., assignors to The Rome Company, Inc., Rome, N. Y., a corporation of New York

Application April 25, 1934, Serial No. 51,519

Term of patent 14 years

To all whom it may concern:

Be it known that we, NORMAN BEL GEDDES and FRANCES R. WAITE, both citizens of the United States, and both residing in New York, in the county and State of New York, have invented a new, original, and ornamental Design for a Bedstead, of which the following is a specification, reference being had to the accompanying drawing, forming part thereof.

The drawing is a perspective view of a bedstead showing our new design.

A feature of the design is the provision in both the head board and the foot board of a central rectangular panel extending from top to bottom

and located between vertical ribs connecting the central panel to relatively narrower rectangular border panels equal in height to the central panel and extending between the ribs and cylindrical bedposts of approximately the height of the panels. The central panel of the foot board is narrower than the central panel of the head board to break the effect of converging lines due to perspective and to give the effect of parallel lines.

We claim:

The ornamental design for a bedstead as shown and described.

NORMAN BEL GEDDES.
FRANCES R. WAITE.
